UNITED STATES PATENT OFFICE

JEROME R. LA VIGNE, OF WATERBURY, CONNECTICUT, ASSIGNOR TO WATERBURY
BUCKLE COMPANY, OF WATERBURY, CONNECTICUT, A CORPORATION

DESIGN FOR A BUCKLE

Application filed February 3, 1930. Serial No. 34,393. Term of patent 3½ years.

To all whom it may concern:

Be it known that I, JEROME R. LA VIGNE, a citizen of the United States, residing at Waterbury, in the county of New Haven and State of Connecticut, have invented a new, original, and ornamental Design for a Buckle, of which the following is a specification, reference being had to the accompanying drawing, forming part thereof.

Fig. 1 is a face view of a buckle showing my new design; and

Fig. 2 is a side view of the same.

I claim:

The ornamental design for a buckle as shown.

J. R. LA VIGNE.
